UNITED STATES PATENT OFFICE.

FRANK C. MOSIER, OF WEST PITTSTON BOROUGH, PENNSYLVANIA.

BARB-WIRE FENCE.

SPECIFICATION forming part of Letters Patent No. 779,616, dated January 10, 1905.

Application filed July 11, 1904. Serial No. 216,032.

To all whom it may concern:

Be it known that I, FRANK C. MOSIER, a citizen of the United States, residing at West Pittston borough, in the county of Luzerne 5 and State of Pennsylvania, have invented certain new and useful Improvements in Barb-Wire Fences; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 My invention relates to barbed-wire fences, and has for its object to provide a barbed wire which can be conveniently handled and can be applied to a fence in a simple and efficient manner.

20 A further object of my invention is to provide a barbed wire which can be stretched in the same manner as a simple wire and which can be passed through the fence-posts, thus obviating the usual stapling and providing a 25 fence which is exceptionally strong and durable.

With these objects in view my invention consists in providing a wire formed spirally and provided with barbs thereon, said spiral 30 barbed wire being passed over a simple straight wire, as will be hereinafter fully described.

Referring to the accompanying drawings, Figure 1 is a perspective view showing a portion of the spiral barbed wire in the act of being passed over the simple straight wire. Fig. 2 is a view showing two fence-posts and illustrating the manner of affixing the wire thereon, and Fig. 3 is a sectional view taken through the wire.

40 Like numerals of reference indicate the same parts throughout the several figures, in which—

1 indicates the simple straight wire, which may be of any suitable metal and of any desired diameter.

45 2 indicates the coiled wire provided with

the barbs 3, which coiled wire is passed over the simple straight wire, as shown in Fig. 1.

Having thus fully described the several parts of my invention, its operation is as follows: Referring to Fig. 2, in which 4 indicates the fence-posts, it will be seen that the straight wire 1 is passed directly through the said posts and is not stapled thereon. In affixing this wire to a fence the spiral barbed wire is 55 cut in lengths corresponding to the spaces between the fence-posts 4 and the straight wire is passed through one of said posts and a section of the spiral barbed wire is slipped over the straight wire. The end of the straight 60 wire is then passed through the next post and the wire is stretched to the desired degree. Another section of the spiral barbed wire is then passed over the straight wire and the end of the straight wire is again carried through 65 the succeeding post, and so on until the fence is complete.

Having thus described the several parts of my invention, I do not wish to be understood as limiting myself to the exact construction 70 as herein set forth, as various slight changes may be made therein which would fall within the limit and scope of my invention, and I consider myself clearly entitled to all such changes and modifications.

75 What I claim as my invention, and desire to secure by Letters Patent of the United States, is—

A barbed wire for the purpose described, comprising a straight wire, a flexible round 80 spiral wire provided with a series of barbs tied thereon, said round spiral wire being passed over said straight wire and adapted to be yieldingly and loosely carried on said straight wire, substantially as described. 85

In testimony whereof I affix my signature in presence of two witnesses.

FRANK C. MOSIER.
